COMBINED CARRYING CASE AND NURSING BOTTLE HOLDER

Harry Siegel, 620 Fort Washington Ave., New York, N.Y.

Filed Aug. 30, 1962, Ser. No. 71,980

Term of patent 14 years

(Cl. D87—5)

FIG. 1 is a front perspective view of a combined carrying case and a nursing bottle holder;

FIG. 2 is a rear perspective view of the same;

FIG. 3 is a sectional view taken on the line 3—3 of FIG. 1; and

FIG. 4 is a sectional view taken on the line 4—4 of FIG. 1.

The dominant feature of my new design consists in the centrally disposed circular temperature indicator on one side of the holder disclosed.

I claim:

The ornamental design for a combined carrying case and nursing bottle holder, substantially as shown and described.
